UNITED STATES PATENT OFFICE.

ABEL E. CHERNACK, OF NEW YORK, N. Y.

RACK FOR MUSIC-ROLLS OR THE LIKE.

1,275,132.

Specification of Letters Patent.

Patented Aug. 6, 1918.

Application filed December 6, 1917. Serial No. 205,762.

To all whom it may concern:

Be it known that I, ABEL E. CHERNACK, a citizen of the United States of America, residing in the city, county, and State of New York, have invented a certain new and useful Improvement in Racks for Music-Rolls or the like, of which the following is a specification.

My invention relates to racks and particularly to a rack for holding music rolls for player pianos, the object of my invention being to provide a relatively inexpensive rack accommodating a large number of rolls and presenting the ends of the roll boxes in position to facilitate the reading of their titles. A further object of my invention is to provide a knock-down rack of such construction that its shelves may be collapsed on the frame and the base detached and confined within the frame, so that when not in use the rack parts may be brought into a small space for packing or storage. Another object of my invention is to provide a structure with parts of such character that they can be cheaply fabricated and standardized, thus insuring low cost of manufacture.

In the accompanying drawings,

Figure 1 is a vertical elevation of a rack in which my invention is embodied in one form;

Fig. 2 is a perspective of one of the rack shelves and portion of the connecting bars;

Fig. 3 is a horizontal section through the rack;

Fig. 4 is a side elevation of the rack collapsed; and

Fig. 5 is a vertical section through the rack in opened position.

The construction here illustrated comprises a base 10 having on its upper face a central boss 11 and tapped hole 12 into which takes the screw stem 13 of a wooden pivot pin 14, provided with a knob 15 to facilitate its insertion. Upon the cylindrical body portion of the screw and beneath the retaining flange 16, is swiveled the bottom bar 17 of an open frame, oblong in plan, the side uprights 18 and 19 of which are united at their upper ends by a cross bar 20 of any suitable type, here shown cylindrical and secured to the uprights by screws 21. Between the uprights 18 and 19 are pivoted, at their inner ends, two series of superposed shelves 22, 23, 24, 25, 26, 27, one series on each side of the mid-plane of

the uprights. At their outer ends the shelves of each series are pivoted to connecting bars 28 and 29, one on each side of the series and serving to maintain the shelves in predetermined spaced relation. At their upper ends the bars 28 and 29 are jointed to links 30 and 31 which have at their inner ends bayonet slot openings 32 adapted to take over pins 33 and 34 on the inner face of the uprights 18 and 19 and so located that when the pins lie at the end of the bayonet slots the links hold the shelves in such inclined position that the titles on the ends of the music roll boxes 35 are presented at an angle which facilitates their reading.

Each shelf has side and bottom flanges 36 which serve to retain the music roll boxes on the shelves. The connecting bars 28 and 29 are preferably of channel section, the ends 37 of the outwardly extended ends 37 of the side flanges 36 lying within the channel 38 and being thus concealed by the bars 28 and 29. The channel 38 is preferably located to one side of the center of the bar so that the thin wall 39 faces the shelf and limits as little as possible the available space for the music roll boxes.

It will be noted that the inclination of the shelves is such that the center of gravity of the rolls supported thereby falls within the area of the base 10. Consequently even were the rack loaded only on one side there would be no danger of tipping it over.

If the rack is to be stored or shipped the links 30 and 31 are disengaged from the pins 33-34 and the shelves folded upward so that they lie between the side uprights 18 and 19 of the frame and are thus protected during shipment. In this position the side bars 28 and 29 lie against the edges of the uprights. It will be noted that the outer ends of the side flanges 36 are cut away to permit this. The pivot pin 15 may also be unscrewed and the detached base 10 may be placed between the shelves and the uprights of the frame, where it may be secured in any convenient way during shipment or storage. It will be noted that the uprights 18 and 19 and their end pieces 17 and 20 form a protective frame surrounding the shelves so that the crating or boxing of the rack is a very simple matter.

The ordinary construction of the present rack comprises six shelves, each accommodating six roll boxes of ordinary size so that the total capacity of the stand is thirty-six

rolls on each side or seventy-two rolls in all. If large boxes are placed upon the two lower shelves on each side, five may be accommodated on each shelf, and the total capacity 5 of the rack is thus lowered to sixty-eight, including the twenty boxes of large size. It will also be noted that the lower two shelves 22, 23, are spaced a slightly greater distance apart than the upper shelves to accommodate 10 the boxes of larger size.

The construction illustrated is adapted for either wood or sheet metal fabrication, and I do not limit myself to either material. The rack can be made in large quantities at much 15 lower cost than an ordinary music roll cabinet, occupies little or no more room in spite of its greater capacity, and presents many obvious practical advantages thereover, in addition to that of economy. Various modifications 20 in detail of construction will readily occur to those skilled in the art which do not depart from what I claim as my invention. Thus for instance, chains may be used instead of the solid links 30 and a plain angle 25 bar may be substituted for the channel bar 28.

I claim:—

1. A rack for player piano roll boxes comprising a floor base, a rectangular frame having bottom, top, and side members rigidly 30 secured together, a swiveling connection between said bottom member of the frame and the base, together with two series of upwardly inclined shelves extending between

said side uprights and facing in opposite directions on opposite sides of the plane of 35 said swiveling axis of the frame, the shelves of each series being of sufficient width to support roll boxes placed thereon at right angles to the length of the shelves and being arranged so closely together and at such 40 angle that the upper ends of the roll boxes on one shelf extend above the lower margin of the shelf next above and the upper ends of the roll boxes on all the shelves are presented at an angle to facilitate the reading of their 45 titles, the inner margins of the shelves of the opposed series being spaced apart to leave a central open area into which the innermost corners of the roll boxes project, and means at the inner margin of each shelf 50 for supporting the lower inner corner of the roll boxes placed thereon, the shelves of each series being pivoted to said side members of the frame and folding upward 55 against each other into a substantially vertical position, the pivots of adjacent shelves being spaced apart a less distance than the width of the shelves.

2. In a construction such as specified in 60 claim 1, means for collapsing the shelves substantially into the plane of the side uprights for storage and shipping purposes.

In testimony whereof I have signed my name to this specification.

ABEL E. CHERNACK.
